SERVICE FITTING FOR UNDERFLOOR WIRING DUCT

De Forest D. Butler, Lexington, Ky., assignor to Square
D Company, Park Ridge, Ill., a corporation of Michigan

Filed July 8, 1965, Ser. No. 86,078

Term of patent 14 years

(Cl. D26—5)

FIG. 1 is a perspective view of a service fitting for underfloor wiring duct, showing one form of my new design wherein the height-to-width ratio is relatively small;

FIG. 2 is a top plan view of the service fitting shown in FIG. 1;

FIG. 3 is a side elevational view of the service fitting shown in FIG. 1, the opposite side being a mirror image thereof;

FIG. 4 is an end elevational view showing one end of the service fitting of FIG. 1;

FIG. 5 is a bottom plan view of the service fitting shown in FIG. 1;

FIG. 6 is an end elevational view showing the other end of the service fitting of FIG. 1;

FIG. 7 is a perspective view of a service fitting for underfloor wiring duct, showing another form of my new design wherein the height-to-width ratio is relatively large;

FIG. 8 is a top plan view of the service fitting shown in FIG. 7;

FIG. 9 is a side elevational view of the service fitting shown in FIG. 7, the opposite side being a mirror image thereof;

FIG. 10 is an end elevational view showing one end of the service fitting of FIG. 7;

FIG. 11 is a bottom plan view of the service fitting shown in FIG. 7; and

FIG. 12 is an end elevational view showing the other end of the service fitting of FIG. 7.

I claim:

The ornamental design for a service fitting for underfloor wiring duct, substantially as shown and described.
